BENJAMIN FRANKLIN HARTWELL, OF WINCHESTER, MASSACHUSETTS.

BOOT OR SHOE, AND COMPOSITE SOLE THEREFOR, AND PROCESS OF MANUFACTURING SAME.

Application filed January 8, 1926. Serial No. 79,992.

My present invention relates to a novel and improved method of manufacturing boots and shoes, a composite sole for use therewith, and the boot and shoe made there-
5 by.

In manufacturing boots and shoes, it is desirable to have a shoe structure with great flexibility in the sole, combined with wear resisting qualities, and a strong heel
10 seat construction. In an effort to accomplish such a result, it has heretofore been attempted to form a composite sole with rubber forepart and leather shank and heel part, but I believe that I am the first to utilize
15 crepe or unvulcanized rubber in such a composite sole construction. In my prior and copending application, Ser. No. 56,145, filed September 14, 1925, I have shown and described my improved sole of combined
20 leather and rubber, and in my present invention I can also employ crepe rubber, applying the same by the well known "two unit" process at present in commercial use.
The principal difficulty has been experienced
25 in attempting to combine a leather and rubber sole, particularly outsoles, because of the difficulty in securing a proper joint between the two materials, the apparent impossibility of permanently cementing rubber and leather,
30 the expense of fashioning intricate joints, and the resulting weakness of the sole at such joints, and the positioning and location
35 of the joint in the sole.

A principal feature of my present invention, therefore, is to obviate such former difficulties and enables me to produce a combined leather and rubber sole, as an outsole for boots and shoes, whether welts, McKays or other types, wherein the full flexibility
40 of the forepart is secured by rubber or a rubberlike composition, preferably crepe rubber, combined with the advantages of a leather shank and heel seat portion for the sole, and novel types of interlocking joints
45 at peculiarly advantageous locations in the shoe sole.

In carrying out my invention I may utilize any of the well-known types of rubber or rubber-like compounds or compositions,
50 including raw, crepe or latex rubber, or combinations of the same, to form a wear resisting and flexible layer of suitable thickness to constitute the outsole of the shoe.

The forepart section is of sufficient length
55 and extent, relatively with the size and style

of the shoe and sole blank, so that this rubber or rubber-like section will be joined to the leather shank and heel portion at a point substantially remote from that portion of the sole which withstands the greatest
60 amount of flexing. By positioning the joint in the shank or arch of the shoe, where no, or substantially no, flexing, bending and working of the sole is required, I avoid many of the difficulties and disadvantages heretofore
65 experienced in making such a jointure between rubber and leather. By my peculiarly interlocking joint arrangements, and at the position which I have discovered is most important in the rigid shank of the shoe, I
70 can partially cement and partially stitch the leather and rubber together, effecting a permanent jointure. By thus having this joint in a protected position under the non-flexing
75 part of the shank or arch, the stitching will not be broken during flexing, the interlocking dovetailed joint arrangements which I
80 prefer to employ, are not endangered or disturbed, and the entire sole is maintained in a desirable and satisfactory manner.

Furthermore, by utilizing my present novel details of construction, I am enabled to satisfactorily join crepe rubber and rubber fiber or other rubberlike compositions, to form an outsole with the advantages of each, viz, with the wear-resisting and tread qualities of crepe rubber, and the toughness and relative rigidity of the rubber fiber or composition.

Further features of the invention, novel combinations of parts, details and advantages, will be hereinafter more fully pointed out and claimed.

Referring to the drawings, illustrating a preferred embodiment of my present invention,

Fig. 1 is a side elevation of one form of my invention applied to a welt shoe;

Fig. 2 is a bottom plan view of the same shoe;

Fig. 3 is a cross-sectional view on the line 3—3 of Fig. 1;

Fig. 4 is a similar cross-sectional view illustrating application to a McKay shoe;

Fig. 5 being a cross-sectional detail on the line 5—5 of Fig. 2.

Although my invention resides primarily in the soles, and methods of joining same, I also consider that I have effected a substantial and novel improvement in the boot or

shoe structures, whether of McKay or welt type, and therefore I claim these features herein.

Fig. 1 illustrates, in side elevation, a conventional welt shoe of the oxford type, wherein the upper 1 has joined to it a welt 2. A fiber or rubber sole member 3, to which is secured a midsole 4 of thin crepe rubber, is then attached to a leather sole member 5 of an area to extend over the shank and heel seat of the shoe. The rubber or fiber sole 3 and midsole 4 of crepe rubber are joined in any suitable manner, by solvents, cements or the like, and each secured to the leather sole member 5 in a scarf 6, provided therefor, in any suitable manner, preferably by stitching 7, and reinforced by cement. As illustrated in Figs. 1 and 2, the fiber sole member 3 is joined to the leather portion by two rows of stitching, while but one row of stitching engages the thin crepe midsole. With this composite sole secured to the shoe, an outsole 8, preferably of crepe rubber, is then joined to the midsole 4 in the usual manner, 25 preferably by coating the contacting surfaces of the soles 4 and 8 with a suitable solvent, such as benzol, and assembling the two soles together, preferably under pressure, until the outsole 8 has unified with the 30 midsole 4 in a firm, homogeneous manner, forming a neat, attractive, firm, strong and efficient shoe structure, and one of great wear-resisting capacity. A conventional heel 9 is illustrated in Fig. 1, which may be 35 of rubber, leather or the like. As shown in Fig. 1 the jointure of the leather and rubber sole members comes substantially at the arch of the shoe, away from the flexing or bending of the sole in walking, and being 40 thus relieved of any liability of breaking away caused by such strains.

Fig. 3 illustrates, in cross-section, the method of attachment of my novel sole to a shoe of the welt type, wherein the upper 45 1, welt 2, and insole 10 are united by inseam stitching 11. To the welt 2 is then attached the composite fiber sole 3 and midsole 4 by welt stitching 12. The outsole 8 is also illustrated in position to be attached to the 50 midsole 4 in any suitable manner, preferably by being unified therewith by coating the two contacting surfaces 13 and 14 with a suitable solvent, and assembling the same, preferably under pressure.

Fig. 4 illustrates the method of attachment to a McKay shoe, wherein the upper 55 15, insole 16 and composite sole 3 and 4, are all united by through and through stitching 17, the outsole 8 being shown in position for attachment similar to the method described in Fig. 3. The advantages of 60 thus having the stitching holding the combined sole 3 and midsole 4, concealed under the outsole 8, and therefore not subjected to wear, will be readily appreciated.

Fig. 5 is a cross-sectional detail illustrating the method of joining of the composite sole, wherein the leather sole member 5 is scarfed as illustrated at 6, the fiber sole member 3 and midsole 4 inserted in this scarf and secured thereto by stitching 7. The sole members and scarf faces may also be cemented together, in addition to the stitching, if desired. The outsole 8 is then applied, after the composite sole above described has been affixed to the shoe, and adhered thereto, the shank end of this outer sole 8 abutting against a shoulder 18 on the leather sole membr 5, to form an even, close fit, and presenting a flush surface throughout the entire length of the sole.

I believe that a shoe thus formed by my novel method is new, and I claim the same herein broadly.

I also believe that my novel composite sole is new, and I claim this herein as well.

The importance and advantages of the shoe construction, and novel composite sole as above described, will be readily apparent to those skilled in the art. The advantageous features of composite soles, with the strength and rigidity of a leather portion in the heel and shank portions, and the resiliency and flexibility of the crepe rubber on the tread surface, are of great importance in this art, and I believe are novel and will appeal, not only to the trade, but to the purchasing public as well, who will realize the benefits and advantages of such shoe constructions.

My invention is further described and defined in the form of claims as follows.

1. A composite sole, comprising a leather shank and heel portion, a forepart composed of a layer of rubber or rubber composition to which is adhered a midsole of crepe rubber, there being an interengaging transverse joint between the leather sole portion and both said rubber layers in a non-flexing part of the arch or shank, and a crepe rubber outsole unified with said crepe rubber midsole.

2. An improved boot or shoe, having a composite sole, comprising a leather shank and heel portion, a forepart composed of a layer of rubber or rubber composition to which is adhered a midsole of crepe rubber, there being an interengaging transverse joint between the leather sole portion and both said rubber layers in a non-flexing part of the arch or shank, said composite sole being secured to the shoe by mechanical fastening devices, and a crepe rubber outsole unified with said crepe rubber midsole and concealing and protecting the mechanical fastening devices in said midsole.

3. The improved process of making boots and shoes, which consists in first assembling an insole and upper materials on a last, lasting the shoe, then applying a composite sole to said shoe, said composite sole comprising

a leather shank and heel portion, a forepart composed of a layer of rubber or rubber composition to which is adhered a midsole of crepe rubber, there being an interengaging transverse joint between the leather sole portion and both said rubber layers in a non-flexing part of the arch or shank, securing this composite sole to the shoe by usual stitching and heel nailing operations, attach-

ing a crepe rubber outsole to said crepe rubber midsole to form a homogeneous unified outsole and concealing the stitching in the midsole, attaching a heel, removing the last and completing the shoe.

In testimony whereof, I have signed my name to this specification.

BENJAMIN FRANKLIN HARTWELL.
